UNITED STATES PATENT OFFICE.

ALFRED T. HOEVET, OF NEW YORK, N. Y., ASSIGNOR, BY MESNE ASSIGNMENTS, TO MOUNT VERNON SPECIALTY COMPANY, A CORPORATION OF NEW YORK.

CIGAR-LIGHTER.

1,027,205.

Specification of Letters Patent. Patented May 21, 1912.

Application filed April 14, 1911, Serial No. 621,056. Renewed March 16, 1912. Serial No. 684,225.

To all whom it may concern:

Be it known that I, ALFRED T. HOEVET, a citizen of the United States of America, and a resident of the city, county, and State of New York, have invented certain new and useful Improvements in Cigar-Lighters, of which the following is a specification.

This invention relates to improvements in pocket cigar lighters and has for its object to provide a cigar lighter of simple and practical construction whereby the same may be manufactured at a very low cost.

Other objects will appear as this specification proceeds.

15 In the accompanying drawing Figure 1 is a vertical sectional view of a cigar lighter embodying my invention. Fig. 2 is a fragmentary view of the igniting wheel, and adjacent parts. Fig. 3 is a detail perspective view of the partition member, and Fig. 4 is a detail view of a cigar cutter adapted to be contained within the cigar lighter.

The reference numeral 5 denotes a casing open at both ends and within which is inserted a partition member 6 bent to form wheel lugs 7, 7, and hinge ears 8, 8. The partition member is soldered to the casing along the edges so as to form a tank 9 adapted to contain fuel such as gasoline, alcohol or the like. Because of the peculiar shape of the partition member there are also formed two spring chambers 10 and 11 as shown. In the chamber 10 there is inserted the locking spring 13 having a button 14 and a catch 15.

16 is the cover having secured thereto a hinge piece 17 provided with an aperture 18. The hinge piece 17 and the hinge ears 8 are joined by a pin to form the hinge 19.

40 20 is an opening spring which is coiled around a pin 21 and the upper end of which passes through the aperture 18 and is provided with a hook 22 forming a stop. The lower end 23 of the spring is bent inwardly away from the casing for the purpose of securing in place a cigar cutter as 24 or other article, as for instance a nail file. The pivot 25 of the cigar cutter illustrated projects into the wall of the casing so that it may be 50 easily gotten hold of and removed by a downward pull. For this reason the bottom of the spring chamber 11 is left open and the wall of the casing is cut away as at 26.

55 27 is a ratchet wheel pivoted in the wheel lugs 7 and provided with side teeth 28

adapted to be engaged by a pawl lever 29 as shown. The latter is pivoted concentrically with the ratchet wheel at 30 and is operated by a pin 31 secured in the cover 16 and which plays in a slot 32 in the pawl 60 lever.

33 is the cover catch.

A spring 41 keeps the lever in engagement with the wheel.

34 is a tube containing the spark metal 35 65 which is pressed up against the wheel 27 by a spring 36. A screw 37 closes the tube 34.

38 is a short tube through which passes the wick 39.

A closure tube 40 fast in the cover extinguishes the flame when the device is closed. A rubber collar 42 may be used to effect air-tight closure by the tube 40. The tank is closed by a bottom 50 having a fuel inlet at 43 which is closed by a metal or other cork 44.

The cover is normally held closed by the spring 13 and catch 33. When the button 14 is pressed inwardly the cover is released and suddenly opened by the spring 20 until the spring hook 22 limits the movement of the cover. As the latter opens the pin 31 oscillates the pawl lever 29 which in turn rotates the wheel sharply which by friction with the spark metal produces sparks which ignite the wick. When the cover is closed the pawl lever passes over the teeth 28 against the pressure of the spring 41.

It will be observed that my cigar lighter 90 comprises but a few parts and is very easily assembled. Also that there is provision for a large fuel supply, yet room enough at both sides of the tank for the springs to work. The spring 22 besides being an opening spring also performs the function of securing the cigar cutter 24.

Various changes may of course be made within the principle of the invention.

I claim:

1. In a cigar lighter the combination of a casing open at both ends, a partition member inserted within said casing to form a tank and separate spring chambers, a bottom secured to the casing and the said partition member, a hinge piece hinged to the said partition member, a cover secured to the said hinge piece which latter is provided with an aperture, an opening spring inserted in the one of the said spring cham- 105
110

bers and passing through the said aperture to limit the opening movement of the cover, a wick within the said tank and projecting therefrom, a mechanism for producing 5 sparks and means for operating the said spark mechanism from the said cover.

2. In a cigar lighter the combination of a casing, a partition member secured within the same, a ratchet wheel journaled on the 10 said member, hinge ears formed integral with the latter, a hinge piece hinged to the said hinge ears, a cover secured to the said hinge piece, a spring secured between the casing and the said partition member for

opening the cover, the said spring engaging 15 the said hinge piece to limit the movement of the cover, spark metal, means for forcing the same into operative contact with the said ratchet wheel and means for operating the latter to produce sparks from the said 20 metal.

Signed at New York, N. Y. this 12th day of April 1911.

ALFRED T. HOEVET.
